UNITED STATES PATENT OFFICE.

HARRY A. DE HAAS, OF MOUNT LEBANON TOWNSHIP, ALLEGHENY COUNTY, PENNSYLVANIA.

SWINGING-WINDOW STRUCTURE.

Application filed April 23, 1925. Serial No. 25,254.

To all whom it may concern:

Be it known that I, HARRY A. DE HAAS, a citizen of the United States of America, and a resident of the township of Mount 5 Lebanon, county of Allegheny, and State of Pennsylvania, have invented a certain new, useful, and Improved Swinging-Window Structure, of which the following is a specification.

10 In general my invention relates to that type of window in which the sash both slides vertically and swings on a horizontal axis relative to the window frame.

In this character of window the sash is 15 pivoted on a horizontal axis between a pair of vertically disposed sash-bars which are in turn slidably mounted in the window frame and which are usually provided with the conventional cords and weights; and my 20 invention particularly relates to the mounting of the sash on the sash-bars and the packing between the same which, without interfering with the pivotal movement of the window, provides an air-tight joint when 25 the sash is vertical and also prevents rattling.

In the accompanying drawings wherein I 30 illustrate the application of my invention, Fig. 1 is an inside elevation of a window frame provided with an upper and lower sash, the upper sash being shown in its closed or vertical position while the lower sash is swung on a horizontal axis into a tilted position; Fig. 2 is an enlarged broken 35 vertical section of a sash taken along the line II-II in Fig. 3; Fig. 3 is a broken horizontal section on enlarged scale and taken along the line III-III in Fig. 2, and Fig. 4 is a broken section on the line IV-IV 40 in Fig. 3.

The following is a detailed description of the drawings.

A is the window frame which is shown of the conventional type provided at its vertical sides with grooves to receive the edges of the upper and lower sash. The upper sash is indicated at B and the lower sash at B'.

50 Preferably both the upper and lower sash are constructed in accordance with my invention, but if desired one of them may be of the ordinary vertical sliding type. The sash are each mounted on a horizontal axis between pairs of sash-bars C which are mounted to slide in the usual sash-grooves

in the window frame A. The bars C are preferably provided with the usual cords and weights.

The edges of the sash and the sash-bar are in flat surface contact when the sash is 60 vertical as shown in Fig. 3. At their centers the sash-bars C are pierced by horizontal circular holes whose outer portions are of greater diameter, thus providing an intermediate shoulder 1. The inner and 65 smaller diameter of the hole is provided with a bushing 2 whose outer end has a foot flange 3 which is countersunk into the outer surface of the sash bar and attached in place by screws 4. 5 is a hollow stud of proper 70 diameter to be journalled in the bushing 2 and which is provided with a foot flange 6 which is countersunk in the edge of the sash and secured by screws 7 to said sash. The bore of the stud 5 is threaded to receive a 75 screw 8 which extends through a washer 9 bearing against the end of the outer bushing 2. Thus the sash is pivoted on a horizontal axis between and to the bars C, the two 80 flanges 3 and 6 forming a metallic bearing which assumes the wear from the wooden elements.

Each vertical edge of the sash is provided 85 with a vertical slot 10 in which is mounted the metal channel member 11, the same being held in place by its rearwardly extending horizontal tongues 12 seated in recesses 13 in the upper and lower ends of the sash and held in place by screws 14.

15 is a metal packing bar having its front 90 edge rounded and which is of proper width to fit in the channel 11. 16 represents screw-bolts extending loosely through holes in the rear wall of the channel member 11 and having their front ends screwed into threaded 95 holes in the bar 15. Helical springs 17 are coiled about said bolts between the rear wall of the channel and the bar, thus resiliently forcing the bar outwardly. The heads of the screw-bolts prevent the dislodgment of 100 the bar from the channel when the sash is swung from the vertical. The sash is provided with sockets 18 in the rear of the channel member to provide clearance for the inner ends and heads of the screw-bolts. 105 Said bolts and springs are provided at proper intervals to properly support the packing bar in position.

Each of the sash-bars is provided with a trough shaped slot 19 which registers with 110

the slot 10 in the sash when the latter is vertical. The slot 19 is provided with a metal trough member 20 which is held in place on the bar by its end tongues 21 seated 5 in recesses in the ends of the bar and attached by screws 22. The trough members 20 are of a flattened arc cross-sectional shape with which the rounded edges of the bars 15 mate and into and out of engagement 10 with which said bars may readily move as the window is swung on its axis.

It is evident that when the sash is in its vertical position the packing bars are forced in a resilient mating with the troughs and 15 that an air-tight and rattle-proof joint is effected. It is further evident that when the window is swung out of the vertical the bars being spring mounted are readily disengaged from the troughs by the application 20 of a slight force. It is also evident that when the window is swung back into the vertical the packing bars will snap into mating engagement with the troughs.

What I desire to claim is:—

- 25 1. In a sliding and swinging window structure the combination with a window frame, of a pair of sash-bars mounted to slide vertically in said frame and a window sash interposed between said bars, of a horizontally disposed journal member sunk into each of said sash-bars, a horizontally disposed stud extending from each vertical edge of said sash and journaled in the corresponding journal member, said studs having threaded bores, washers bearing against the ends of said journal members and studs, and screws extending through said washers and screwed into the threaded bores of said studs.
- 40 2. In a sliding and swinging window structure, the combination with a window frame, of a pair of sash-bars mounted to slide vertically in said frame and a window sash interposed between said bars, of a horizontally disposed bushing sunk into each of said sash-bars, a horizontally disposed stud extending from each vertical edge of said sash and journaled in the corresponding bushing, said studs having threaded bores, washers bearing against the ends of said bushings and studs, and screws extending through said washers and screwed into the threaded bores of said studs.
- 45 3. In a sliding and swinging window structure, the combination with a window frame, of a pair of sash-bars mounted to slide vertically in said frame and a window

sash interposed between said bars, of a horizontally disposed bushing sunk into each of said sash-bars and provided with a foot flange substantially flush with the surface of the bar, a horizontally disposed stud extending from each vertical edge of the sash and journaled in the corresponding bushing, said stud having a foot flange in flat contact with the foot flange of the bushing, said studs being provided with threaded bores, washers bearing against the ends of said bushings and studs, and screws extending through said washers and screwed into the threaded bores of said studs.

4. In a sliding and swinging window structure, the combination with a window frame, of a pair of bars mounted to slide vertically therein and each having a vertical slot on its inner face, means whereby a sash is pivotally mounted between said bars to swing on a horizontal axis, said sash interposed between said sash-bars and provided with vertical side grooves, a metal channel member mounted in each of said grooves, a packing-bar having its outer end contoured to fit the slot on the sash-bar, members fixed to said packing-bar and extending through the rear wall of said metal channel, helical springs coiled about said members and tending to press said packing-bar outwardly, the inner ends of said members being provided with heads to prevent their disengagement from said channels.

5. In a sliding and swinging window structure, the combination with a window frame, of a pair of bars mounted to slide vertically therein and each having a vertical slot on its inner face, means whereby a sash is pivotally mounted between said bars to swing on a horizontal axis, said sash interposed between said sash-bars and provided with vertical side grooves, a metal channel member mounted in each of said grooves, a packing-bar having its outer end contoured to fit the slot on the sash-bar, bolts having their threaded ends fixed to the packing-bar and extending rearwardly through the rear wall of the channel, and helical springs coiled about said bolts between the packing bar and the rear wall of the channel whereby said packing-bar is resiliently pressed outwardly, the heads of said bolts by engaging the rear of said channel preventing the dislodgment of the packing-bar from its channel.

Signed at Pittsburgh, Pa., this 11th day of April, 1925.

HARRY A. DE HAAS.
